Primary Examiner — Dana K Weiland*Assistant Examiner* — Messina L Smith(74) *Attorney, Agent, or Firm* — Loeb & Loeb LLP**CLAIM**

The ornamental design for an electric fryer, as shown and described.

DESCRIPTION

FIG. 1 is a perspective view of an electric fryer showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines depict portions of the electric fryer that form no part of the claimed design.
